UNITED STATES PATENT OFFICE.

DANIEL W. TOWER, OF GRAND RAPIDS, MICHIGAN, ASSIGNOR TO THE GRAND RAPIDS BRASS COMPANY, OF SAME PLACE.

DESK-LID SUPPORT.

SPECIFICATION forming part of Letters Patent No. 576,972, dated February 9, 1897.

Application filed May 22, 1896. Serial No. 592,658. (No model.)

To all whom it may concern:

Be it known that I, DANIEL W. TOWER, a citizen of the United States, residing at the city of Grand Rapids, in the county of Kent 5 and State of Michigan, have invented certain new and useful Improvements in Desk-Lid Supports, of which the following is a specification.

My invention relates to certain new and 10 useful improvements in desk-lid supports; and the invention consists in the features of construction and the combination or arrangement of parts hereinafter described and claimed, whereby the desk-lid is connected 15 with the desk-case and when swung to its open position for use is firmly supported.

The invention is illustrated by the accompanying drawings, in which—

Figure 1 shows a sectional view of a desk 20 with the lid open, showing the pivotal connection between the supporting-arm and the lid and the plate connection between the upper end of the supporting-arm and the end of the desk-case. Fig. 2 shows a side elevation of the desk-lid support, together with the pivotal connection and plate, the same being detached from the desk. Fig. 3 shows an edge view of the parts shown in Fig. 2. Fig. 4 shows a plan view from the inner side 25 of the connecting-plate, with a portion cut away in order to show the locking projection H, which is adapted to retain the upper end of the supporting-arm in position.

Similar letters refer to similar parts throughout the several views.

A represents the desk or case to which my invention is applied.

B represents the lid when opened, as shown in the drawings.

40 C represents the pivotal connection between the lid and the supporting-arm.

E represents the attaching-plate and guide for the upper end of the supporting-arm D. The plate E is constructed with an offset 45 projection G, containing a slot or opening in which the lid-supporting arm D is susceptible of sliding lengthwise, so that the arm moves along one side of the plate E, as will be readily

understood by reference to Figs. 2 and 3. The offset projection G is constructed with two 50 oppositely-arranged bent flanges G', which lap around the opposite parallel edges of the arm D and retain this arm and the offset projection G of the plate E in proper relative position at all times. The desk-supporting arm 55 D is pivoted at one end to the pivotal connection or plate C and at its opposite end is formed or provided with a shoulder or offset F, constituting a stop which is adapted to strike one edge of the slot in the offset projection G when 60 the desk-lid is swung to its open position, as in Fig. 1. The engagement of the stop F with the offset projection G of the plate E serves to firmly support the desk-lid when it is thrown open for use. The plate E is also provided with a projecting lip H, lying substantially in the plane of the plate and adapted to bear against one surface of the supporting-arm D, as will be understood by reference to Fig. 2.

70 L represents the screw or bolt which attaches the plate E to the side of the case, and in the form shown in Figs. 1, 2, and 3 the plate E oscillates upon the bolt or screw L as the desk-lid is raised and lowered, thereby 75 preventing absolutely the supporting-arm D from binding in the way in plate E.

Having thus described my invention, what I claim to have invented, and desire to secure by Letters Patent, is—

80 1. The combination with the hinged lid of a desk, of a guide-plate connected with the desk-case and having a slotted offset projection provided with opposite bent flanges G, and a lid-sustaining arm slidable under said 85 bent flanges and through said offset projection, said arm being pivoted at one end portion to the desk-lid and having an offset-stop at its other end portion which strikes the slotted offset projection of the guide-plate 90 and firmly supports the desk-lid when the latter is thrown open for use, substantially as described.

2. The combination with a desk and desk-lid of a lid-supporting arm pivoted at one end 95 to the lid, a supporting-plate pivoted upon

the desk and having a projecting bracket provided with a way or guide for the lid-supporting arm, a stop on one end of the said desk-lid support to engage a projection on the pivoted plate and serve as a stop, substantially as described.

In witness whereof I have hereunto set my

hand and seal in the presence of two witnesses.

DANIEL W. TOWER. [L. S.]
